UNITED STATES PATENT OFFICE.

GEORGE NEILSON, OF CHELSEA, MASSACHUSETTS.

PROCESS OF TREATING IRON.

SPECIFICATION forming part of Letters Patent No. 281,784, dated July 24, 1883.

Application filed November 9, 1882. (No specimens.)

To all whom it may concern:

Be it known that I, GEORGE NEILSON, of Chelsea, in the county of Suffolk and State of Massachusetts, have invented certain new and useful Improvements in the Process of Treating Iron, of which the following is a specification.

My invention relates to a process for giving to sheet-iron a smooth, hard, and ornamental surface, said surface not being affected by any substances liable to come in contact with it, nor by any ordinary heating to which it may be exposed; and it consists in forming upon the surface of the iron a coating of the carbonate of cobalt, this carbonate of cobalt having a natural affinity for iron, and not susceptible to changes produced by chemical or thermic action.

To work my invention I proceed as follows: The iron, after being carefully selected, cleansed, and polished, is covered with a mixture of cobalt and some unctuous or fluid carbonaceous compound as a vehicle. The amount of cobalt used is not fixed, as a small quantity (one-fourth of an ounce to the square foot) will produce good results, although in some cases larger quantities may be desirable. The amount of vehicle required should be suffi-

cient to make such a mixture as will admit of ready application by brush or otherwise to the surface of the iron, and to be sufficiently rich in carbon to supply the quantity required to form the carbonate of cobalt. After the coating is applied the iron is placed in a furnace and its temperature raised to a red heat, and so maintained until the vehicle is fully carbonized and the carbonate of cobalt formed. The iron is then removed from the furnace, and, after being sufficiently cooled, is immersed in oil. It is then dried by the application of heat and subjected to a hammering or rolling process until the desired degree of polish and hardness is obtained.

I claim—

The above-described process, consisting of the following steps: first, preparing the surface of the iron; second, coating the same with a compound of cobalt and a carbonaceous vehicle; third, heating the same; fourth, covering with oil; fifth, hardening the surface, all substantially as described, and for the purpose set forth.

GEORGE NEILSON.
